UNITED STATES PATENT OFFICE

JAKOB WIKSCHTRÖM, OF DUSSELDORF, GERMANY

TOOL FOR MANUFACTURING WIRE-TACKS AND NAILS

Application filed August 18, 1930, Serial No. 475,999, and in Germany September 11, 1929.

My invention relates to tools for manufacturing wire-tacks and nails by which a piece of wire is provided with a head and a point without waste.

5 Tools of this type are equipped with chucking and swaging means for forming the head of the nails, and cutting means for forming the point. The chucking and swaging means includes a pair of cooperating reciprocating dies or jaws and the cutting means includes a pair of cooperating and reciprocating cutters.

10 It is an object of my invention to improve a tool of this type. To this end I provide the chucking and swaging means, and also the cutting means, with a pair of circular reciprocating discs, and equip the discs with chucking and swaging elements, and with knives, respectively, on their edges.

15 It has already been proposed to provide tools having a plurality of chucking and swaging elements, and also a plurality of knives, so that when the elements or knives which have cooperated for a given time, have become worn, they may be exchanged by other elements or knives. In such tools, however, the knives were formed on the end of a circular bar which was adapted to be rotated about its axis for exchanging the knives. Obviously the space available for the knives is limited in such a bar. By providing circular discs according to my invention for the chucking and swaging, and for the cutting means, I may arrange a practically unlimited number of elements and knives by suitably selecting the diameter of the discs, and present any desired combination of elements and knives to the blank by rotating the discs.

20 It is another object of my invention to provide an improved cutter for a tool of the kind described. To this end I arrange the knives on the edge of the cutter alternately in reversed positions, and preferably so that each cutting edge forms part of two adjacent knives.

25 By arranging the knives in the manner described I obtain two sets of knives on a single cutter which are placed into active position by turning the cutter through an

angle of 180°. By these means, the space available on the edge of the cutter is utilized to great advantage, and the space economy is further increased by arranging two adjacent knives with a single cutting edge. The machining and grinding of the cutters are also facilitated by the said arrangement.

30 In the drawings affixed to this specification and forming part thereof a tool embodying my invention is illustrated diagrammatically by way of example.

In the drawings:

Fig. 1 is an elevation showing the chucking and swaging means during swaging,

Fig. 2 is an elevation showing the cutting means during cutting.

Fig. 3 is a plan view of the four discs constituting the means, with one of the cutters broken away to show the chucking and swaging disc below.

Fig. 4 shows part of the perimeter of a chucking and swaging disc, and

Fig. 5 shows part of the perimeter of a cutter, developed,

Fig. 6 shows a portion of Fig. 5, drawn to a larger scale,

Fig. 7 is a section on the line VII—VII in Fig. 6,

Fig. 8 is an end elevation, viewed in the direction of the arrow α in Fig. 6, and

Fig. 9 is a perspective illustration of the cutter portion shown in Fig. 6, viewed in the direction of the arrow γ , Fig. 6.

Referring now to the drawings, and first to Figs. 1 to 3, 1 and 2 are the two chucking and swaging discs, and 3 and 4 are the two cutter disc, 5 and 6 are supports for pins 7 and 8 on which the discs 1 and 2 are mounted to rotate, and 9, 10 are supports for the pins 11 and 12 of the cutters 3 and 4. Reciprocating movement is imparted to the supports by any suitable, and preferably automatic, means for moving the discs into active and inactive position with respect to the blank or wire 13.

14 are chucking grooves in the perimeters of the discs 1 and 2, and 15 are tapered extensions at the ends of the grooves. At the chucking and swaging station S, Fig. 3, two grooves 14 make up a passage of square sec-

tion for the reception of the blank 13 and two extensions 15 make up a tapered depression in which the head of the nail is swaged by a reciprocating plunger 16. 17 is a feed slide by which the nail after its head 18 has been swaged is moved into the position illustrated in Fig. 2, with its end presented to the cutters 3 and 4 which form the point of the nail by means of cutting edges 19 formed in their edges as will be described in detail below. The means for operating the supports 5, 6 and 9, 10, the plunger 16 and the feed slide 17, with the means for moving the blank 13 axially, have not been shown as they form no part 15 of the present invention.

Referring now to Figs. 5 to 9, the cutting edges 19 are arranged in converging relation, with their intersecting points 20 alternately at opposite sides of the cutter as shown for 20 the cutter 4 in Fig. 5, but at some distance from the faces of the cutter. The faces of the cutter are beveled from the points of intersection as best seen in Fig. 7 and two short cutting edges 21 and 22 are obtained by milling a V-shaped groove with its ridge 23 extending inwardly from the point of intersection 20 at an angle to the face of the cutter. By beveling the edges of the cutter from the intersecting points 20, these points are supported and 25 braced by the material of the cutter. Without the bevels, the points of intersection would be in the faces of the cutter, and the edges would be very delicate at this point. The faces at the sides of the ridges 23 intersect the faces extending from the two cutting edges 19 at an obtuse angle so that the edges are effectively braced at 20.

Referring now again to Fig. 6, it will appear from this figure that the edge of the cutter is built up from two sets of oppositely directed knives. For instance, the cutting edge 19 which has been marked *a* is formed by the inclined faces I and II while the cutting edge *b* which intersects the edge *a* at 20*a* is formed by the faces III and IV. *c* is the cutting edge which intersects with the cutting edge *a* at the opposite point 20*b* and is formed by the faces V and VI. The point of the nail is formed by the edges *a* and *b*, with 40 the faces I and III, and the mating edges and faces of the other cutter. When the cutters are turned through 180°, the point will be formed by the cutting edges *a* and *c*, the faces II and V, and the cooperating elements of 45 the other cutter.

If tapered instead of pyramidal points are required, the cutting edges are obtained by milling conical grooves into the edges of the cutters.

50 In order to exchange two cooperating elements of the chucking and swaging discs 1, 2, and the cutters 3, 4, the discs are rotated so as to present other elements to the blank at the swaging station S and the pointing station 55 P, Fig. 3.

In order to exchange the two sets of knives on the cutter, the cutter is turned through 180°, as mentioned.

I wish it to be understood that I do not desire to be limited to the exact details of construction shown and described for obvious modifications will occur to a person skilled in the art.

In the claims affixed to this specification no selection of any particular modification of the invention is intended to the exclusion of other modifications thereof and the right to subsequently make claim to any modification not covered by these claims is expressly reserved.

I claim:—

1. In a machine for making wire-tacks and nails, a pair of circular chucking and swaging dies, a pair of circular point cutters, means for moving the dies and the cutters in each pair alternately into and out of relative co-operating position, and means for presenting a blank to said cutters after it has been released by said chucking and swaging dies, said chucking and swaging dies having head-forming cavities and said cutters having recesses with cutting edges formed between them, said cavities and recesses being arranged alternately in opposite positions with respect to the end faces of said dies and said cutters.

2. In a machine for making wire tacks and nails, a pair of circular chucking and swaging dies, a pair of circular point cutters, supports on which said dies and cutters are rotatably mounted, means for moving said supports with the dies and the cutters in each pair alternately into and out of relative co-operating position, and means for presenting a blank to said cutters after it has been released by said chucking and swaging dies, said chucking and swaging dies having head-forming cavities and said cutters having recesses with cutting edges formed between them, said cavities and recesses being arranged alternately in opposite positions with respect to the end faces of said dies and said cutters.

In testimony whereof I affix my signature.

JAKOB WIKSCHTRÖM.
